US00D993949S

(12) **United States Design Patent** (10) **Patent No.:** **US D993,949 S**
Kelsch et al. (45) **Date of Patent:** **** Aug. 1, 2023**

(54) **SECURITY BRACKET FOR A FOLDABLE ELECTRONIC GADGET**

(71) Applicants: **Christopher A. Kelsch**, Palm Harbor, FL (US); **Vanguard Products Group, Inc.**, Oldsmar, FL (US)

(72) Inventors: **Christopher A. Kelsch**, Palm Harbor, FL (US); **Wade Zhu**, Tampa, FL (US)

(73) Assignee: **Vanguard Products Group, Inc.**, Oldsmar, FL (US)

(**) Term: **15 Years**

(21) Appl. No.: **29/863,016**

(22) Filed: **Dec. 14, 2022**

(51) LOC (14) Cl. **14-03**

(52) U.S. Cl.

USPC **D14/253; D14/447**

(57) **CLAIM**

The ornamental design for a security bracket for a foldable electronic gadget, as shown and described.

DESCRIPTION

FIG. 1 is a perspective front view of a security bracket for a foldable electronic gadget showing the claimed design; FIG. 2 is a perspective back view thereof; FIG. 3 is a front view thereof; FIG. 4 is a back view thereof; FIG. 5 is a right view thereof; FIG. 6 is a left view thereof; FIG. 7 is a top view thereof; FIG. 8 is a bottom view thereof; and, FIG. 9 is a perspective back view thereof depicting an exemplary foldable electronic gadget secured therein. The broken lines illustrate portions of the security bracket for a foldable electronic gadget that form no part of the claimed design. Additional broken lines showing a foldable electronic gadget in FIG. 9 illustrate environmental subject matter and form no part of the claimed design.

1 Claim, 7 Drawing Sheets
